(57) **CLAIM**

I claim the ornamental design for the dresser mirror, as shown and described.

DESCRIPTION

FIG. 1 is a front elevational view of a dresser mirror showing my new design;

FIG. 2 is left-side elevational view thereof;

FIG. 3 is right-side elevational view thereof;

FIG. 4 is a top plan view thereof;

FIG. 5 left front elevational detail of a portion of the carving illustrating the ornamentation thereof in enlarged detail; and, FIG. 6 is a front top center elevational front detail of the dresser mirror illustrating the ornamentation thereon in enlarged detail.

The claimed design does not include any specific depth for the specific ornamental details shown within the perimeter moldings.
